UNITED STATES PATENT OFFICE.

JOHN ALLARD, OF KEWANEE, ILLINOIS.

EXTENSION SHADE-ROLLER.

SPECIFICATION forming part of Letters Patent No. 655,678, dated August 14, 1900.

Application filed May 29, 1900. Serial No. 18,416. (No model.)

To all whom it may concern:

Be it known that I, JOHN ALLARD, a citizen of the United States, residing at Kewanee, in the county of Henry and State of Illinois, have 5 invented a new and useful Extension Curtain-Pole, of which the following is a specification.

This invention relates to shade-rollers, and has for one object to provide improved means for adjustably securing the shade to the roller, 10 so that the former may be conveniently adjusted to suit the length of the window to which the shade may be applied. It is furthermore designed to provide for securing the shade without damaging the latter by the insertion of tacks or similar fastening devices 15 and to arrange for the convenient removal of the shade from the roller.

With these and other objects in view the present invention consists in the combination 20 and arrangement of parts, as will be herein-after more fully described, shown in the accompanying drawings, and particularly pointed out in the appended claims, it being understood that changes in the form, proportion, 25 size, and minor details may be made within the scope of the claims without departing from the spirit or sacrificing any of the advantages of the invention.

In the drawings, Figure 1 is a front elevation of a shade-roller having a shade connected thereto by means of the present invention. Fig. 2 is an enlarged detail longitudinal sectional view taken through one end of the roller. Fig. 3 is a detail perspective view 35 of one of the fastening-caps for securing the shade to the roller.

Corresponding parts in the figures of the drawings are designated by like characters of reference.

Referring to the accompanying drawings, 40 1 designates the roller, which may be a metallic tube, as shown in the drawings, or an ordinary wooden stick, as may be desired.

Removably fitted to each end of the roller 45 is a fastening-cap 2, which is cylindrical in shape and is provided with a plurality of longitudinal slots or incisions to form the spring tongues or fingers 3, which are designed to embrace the adjacent end of the 50 roller, as shown in Figs. 1 and 2. Extending transversely across the inner end of one of the slots or incisions in the cap is a lateral

slot 4 to form a bayonet-slot for the reception of a headed stud or pin 5, projecting out from the roller, whereby the cap may be held 55 against longitudinal displacement from the roller.

To secure the shade 6 to the roller, the former is folded or wrapped upon the roller, after which the caps are applied to the opposite 60 ends of the roller, so that the spring-fingers thereof may embrace the respective longitudinal edges of the shade, which is wrapped upon the roller, whereby the former is held to the roller without being damaged by the 65 insertion of tacks or the like and the roller is also protected against similar damage. It will now be apparent that the shade may be rolled upon the roller as much as may be required to adjust the shade to the length of 70 any particular window, and when the shade is partly rolled up it covers and conceals the spring-fingers of the fastening-caps.

The outer end of each cap is provided with an enlarged cylindrical head 7, which is hollow, so as to form a box or casing, and is provided with a fixed outer end or cover 8. Extending loosely from a central opening in the inner end of the head is a pintle or journal 9, which projects outwardly through an opening 10 in the center of the cover, so that the outer end of the pintle may be supported in an ordinary roller-bracket. (Not shown in the drawings.) Housed within the hollow head or casing is a coiled spring 11, which 85 has its inner end connected to the pintle and its outer opposite end connected to the casing, so as to provide a spring-actuated roller. Pivoted to the inner side of the cover or outer head of the casing is a pair of pawls or dogs 90 12, which are arranged for engagement with a ratchet-disk 13 upon the pintle, whereby the spring and the ratchet device are all housed and protected within the hollow head of the cap.

What is claimed is—

1. The combination with a shade-roller, having studs adjacent to the opposite ends thereof, of a shade having one end rolled upon the roller, and opposite fastening-caps fitted 100 to the respective ends of the roller and embracing the adjacent edges of the rolled portion of the shade, and also provided with bayonet-slots receiving the respective studs,

whereby the caps are fixedly held upon the roller.

2. The combination with a shade-roller, having lateral studs adjacent to the opposite ends thereof, of a shade having one end rolled upon the roller and between the studs, and opposite tubular fastening-caps fitted to the respective ends of the roller, and provided with a plurality of longitudinal incisions or slots, forming spring-fingers to embrace the adjacent edges of the folded portion of the

shade, and also provided with a transverse slot extending across the inner end of one of the longitudinal slots, forming a bayonet-slot for the reception of the adjacent stud.

In testimony that I claim the foregoing as my own I have hereto affixed my signature in the presence of two witnesses.

JOHN ALLARD.

Witnesses:

WALTER KEARNS,
EDWARD ARMSTRONG.
